Patented Jan. 3, 1899.

C. A. W. & D. DEVORE.

BILLIARD CUE CHALKER.

(Application filed Mar. 7, 1898.)

(No Model.)

UNITED STATES PATENT OFFICE.

CLARK A. W. DEVORE AND DAVID DEVORE, OF MONONGAHELA CITY, PENNSYLVANIA.

BILLIARD-CUE CHALKER.

SPECIFICATION forming part of Letters Patent No. 617,231, dated January 3, 1899.

Application filed March 7, 1898. Serial No. 672,838. (No model.)

To all whom it may concern:

Be it known that we, CLARK A. W. DEVORE and DAVID DEVORE, citizens of the United States of America, residing at Monongahela City, in the county of Washington and State of Pennsylvania, have invented certain new and useful Improvements in Billiard-Cue Chalkers, of which the following is a specification, reference being had therein to the accompanying drawings.

This invention relates to certain new and useful improvements in cue-chalkers; and it has for its object to provide novel and effective means for applying the chalk to a billiard and pool cue tip.

The device comprises a cylinder within which the chalk is held near one end and is adapted to be depressed and revolved by the pressure of the cue against the same. The revolving motion of the chalk may be accomplished either by providing the cylinder with spirally-arranged grooves, in which the pins carried by the chalk-receptacle are adapted to travel, so as to revolve the receptacle and chalk as the same is depressed in the cylinder by the pressure of the cue against the chalk. This rotary motion of the chalk may also be obtained by arranging a worm-screw within the cylinder, said screw carrying the chalk-receptacle on its upper end and the threads thereof engaging with the two pins which are provided for this purpose, so as to revolve the worm-screw as it is depressed. In either form of construction a counterbalance-spring is provided for the purpose of returning the chalk to its normal position.

In describing the invention in detail reference is had to the accompanying drawings, forming a part of this specification, and where in like letters of reference indicate similar parts throughout the several views, in which—

Figure 1 is a top plan view of our improved cue-chalker, showing the cylinder provided with spiral grooves. Fig. 2 is a longitudinal sectional view of the same. Fig. 3 is a perspective view of the chalk-holder employed in this form of construction. Fig. 4 is a plan view of the bearing-plate for the chalk-holder. Fig. 5 is a horizontal sectional view of the same. Fig. 6 is a top plan view of a modified form of construction. Fig. 7 is a longitudinal

sectional view of this form of construction. Fig. 8 is a transverse vertical sectional view, taken on the line X X of Fig. 6, with the worm-screw removed. Fig. 9 is an end view of the device.

To put our invention into practice, we provide a cylinder *a*, which may be secured to a suitable bed-plate *b* in any desired manner, the latter being provided with apertures *c* for fastening the same firmly to the billiard-table or in any position where it is desired to locate the chalker. This cylinder *a* in the form of construction shown in Figs. 1 and 2 is provided with spirally-arranged grooves *d*, which are adapted to receive the pins *e*, carried in opposite sides of the cup *f*, which holds the chalk *g*. The recess of this cup is preferably square in its form, as shown at *f'*, so that the block of chalk will be held firmly therein and prevented from rotating except in unison with the cup or holder. The rear end of the cylinder *a* may be closed by an ordinary screw-cap *h*, while the front end of the same is closed by a cap *k*, which is provided with a scoop-shaped mouth *k'*, the extending portion of this scoop-shaped mouth forming a support for the cue near its tip and serving to hold the tip more evenly in engagement with the chalk. The cylinder when provided with the spirally-arranged groove *d* may be strengthened by means of the bar *d'*, extending along the top of the same throughout its entire length, and which may be soldered or otherwise secured to the cylinder. This bar serves the same purpose on the top of the cylinder as the plate *b* serves on the underneath side of the same.

The cap *k* is locked in position by means of pins *l*, arranged near the end of the cylinder *a*, and which are adapted to enter the angle-slots *l'*, provided therefor in the rim of the said cap *k*. By this construction this front cap may be readily removed to place a new piece of chalk in position in the cylinder.

The cup *f* is provided on its underneath face with a centrally-arranged pivot *f'*, which engages in the bearing-plate *f''*, this plate being provided with flanges *f'''* and *f''''*, the latter being arranged interiorly of the former and thereby forming a circumferential groove *f''''*, which receives the upper end of the spiral

retracting-spring m , arranged within the cylinder between the aforesaid bearing-plate and the cap h .

In Figs. 6 and 7 we have shown a modified form of construction in which a worm-screw is provided to accomplish the rotating of the chalk when the pressure of the cue is brought to bear against the same in the same manner as is accomplished by the cup f and the spiral groove provided in the cylinder shown in Figs. 1 and 2. In this form of construction we employ the plate b , of the same form as heretofore described, and secure the cylinder a' firmly thereto. The same form of front cap k and scoop-shaped mouth k' may be employed in this form of construction, and the cap may also be secured firmly in its position in the same manner as before described. In this form of construction we secure the rear end of the cylinder and cap h' , which is formed integral with the sleeve h^2 , of less diameter than the cylinder and which receives the one end of the tube h^3 , closed at its lower end by an ordinary screw-cap h^4 . This tube h^3 has arranged therein the retracting-spring h^5 , which supports the bearing-plate g' , provided in its upper face with the concave recess g^2 , which receives the pointed end of the worm-screw g^4 . On the upper end of this worm-screw is secured the cup g^5 , which receives and holds the chalk. The rotary motion is communicated to the worm-screw as it is depressed by means of screws or pins k^2 , which are supported by the sleeve h^2 and engaged within the spiral grooves of the worm-screw.

It will be observed that in either of these constructions the principle involved is the same, and when the tip of the cue is placed against the chalk and pressure brought to bear upon said cue the chalk will be forced inwardly within the cylinder a or a' and will also be rotated during its said inward movement, so as to apply the chalk to the cue-tip. When the pressure upon the cue is relieved, the retracting-spring m or h^5 will immediately return the cup and its chalk to the front end of the cylinder, where it is again in position for use.

It will be noted that various changes may be made in the details of construction with-

out departing from the general spirit of our invention.

Having fully described our invention, what we claim as new, and desire to secure by Letters Patent, is—

1. In a device of the character described, the combination of a cylinder, a base-plate to which said cylinder is secured, a screw-cap engaging the forward end of said cylinder and provided with a scoop-shaped mouth, a screw-cap engaging the rear end of said cylinder and having formed integral therewith a sleeve of less diameter than the cylinder, a chalk-cup arranged within said cylinder, a worm-screw connected to the base of said chalk-cup the rear end thereof being pointed and extending into the sleeve, a tube engaging in said sleeve, a screw-cap engaging the rear end of said tube, a bearing-plate arranged within the tube and provided on its front face with a recess to receive the pointed end of the worm-screw, pins secured in the sleeve on two opposite sides and engaging the worm-screw to impart a rotary motion thereto when the screw is depressed within the tube, and a retracting-spring arranged in said tube between the bearing-plate and the screw-cap to return the screw to its normal position, substantially as shown and described.

2. A device of the character described comprising a cylinder, a chalk-cup mounted in said cylinder, a base-plate to which said cylinder is secured, a cap engaging the forward end of said cylinder and provided with a scoop-shaped mouth, having an extending portion, a screw-cap engaging the lower end of said cylinder and means whereby the chalk is normally retained against the forward end of the cylinder, and additional means whereby the chalk-cup is rotated when the chalk is pressed upon by the cue, substantially as described.

In testimony whereof we affix our signatures in the presence of two witnesses.

CLARK A. W. DEVORE.
DAVID DEVORE.
